UNITED STATES PATENT OFFICE.

HENRY W. COOK, OF SYRACUSE, NEW YORK, ASSIGNOR TO A. E. NETTLETON COMPANY,
OF SYRACUSE, NEW YORK, A CORPORATION OF NEW YORK.

DESIGN FOR A CREDIT CARD.

Application filed February 10, 1927. Serial No. 20,667. Term of patent 14 years.

To all whom it may concern:

Be it known that I, HENRY W. Cook, a citizen of the United States of America, residing in the city of Syracuse, county of Onondaga, State of New York, have invented a new, original, and ornamental Design for Credit Card, of which the following is a specification, reference being had to the accompanying drawing forming part thereof. The drawing represents a front face view of a credit card embodying the subject-matter of my invention.

The lining on the drawing corresponds to the conventional color and contrasting shades of the same color lining adopted by the Patent Office which color constitutes an important feature of the design.

I claim:

The ornamental design for a credit card substantially as shown and described.

HENRY W. COOK.
